UNITED STATES PATENT OFFICE.

JAMES S. RAY, OF EAST HADDAM, CONNECTICUT.

DESIGN FOR COFFIN-HANDLE SOCKET.

Specification forming part of Design No. 6,584, dated April 8, 1873; application filed March 24, 1873.

To all whom it may concern:

Be it known that I, JAMES S. RAY, of East Haddam, in the county of Middlesex and State of Connecticut, have invented a new and original Design for a Coffin-Handle Socket, of which the following is a specification:

Figure 1 represents a face view of my new design for a coffin-handle socket. Figs. 2 and 3 are profile sectional views thereof on the lines *c c* and *h h*, respectively.

Similar letters of reference indicate corresponding parts in all the figures.

This invention relates to a new configuration and ornamentation of the socket for a coffin-handle. The same is, at its base, of oval outline, with pointed projections *a a* and *b b* at the ends of its long and short diameters. Upon a base of this outline is supported an octago-

nal central field, *d*. The sides *e e* of the socket between this field and the edge of the base are ogee-shaped in profile, as shown, and divided from their surfaces into alternately raised and depressed sections, the latter having corrugated edges *f*, as shown. A recess, *s*, for the reception of the arm is formed in the middle portion of the socket longitudinally, as clearly shown.

I claim as new and desire to secure by Letters Patent—

The design for the socket of a coffin-handle, as shown.

JAS. S. RAY.
